(57) **CLAIM**

The ornamental design for an evacuation chair, as shown and described.

DESCRIPTION

FIG. 1 is a side view of an evacuation chair showing our new design in a closed position;

FIG. 2 is a front view thereof;

FIG. 3 is a rear view thereof;

FIG. 4 is a rear perspective view thereof;

FIG. 5 is a side perspective view thereof, showing the evacuation chair in an open position;

FIG. 6 is another side perspective view thereof, showing the handle in an alternate position;

FIG. 7 is a front perspective view thereof, showing the arms in an alternate position;

FIG. 8 is a front view thereof;

FIG. 9 is a side view thereof; and,

FIG. 10 is a rear view thereof.

The broken lines in the Figures show unclaimed environment and form no part of the claimed design.
